(No Model.)

W. H. WHITFIELD & M. McCORMICK.
ROAD CART.

No. 461,462.

Patented Oct. 20, 1891.

UNITED STATES PATENT OFFICE.

WILLIAM H. WHITFIELD AND MICHAEL MCCORMICK, OF PENN YAN,
NEW YORK.

ROAD-CART.

SPECIFICATION forming part of Letters Patent No. 461,462, dated October 20, 1891.

Application filed June 25, 1891. Serial No. 397,445. (No model.)

To all whom it may concern:

Be it known that we, WILLIAM H. WHITFIELD and MICHAEL MCCORMICK, citizens of the United States, residing at Penn Yan, in the county of Yates and State of New York, have invented certain new and useful Improvements in Road-Carts; and we do hereby declare the following to be a full, clear, and exact description of the invention, such as will enable others skilled in the art to which it appertains to make and use the same.

The invention relates to improvements in road-carts.

The object of the invention is to produce a road-cart having an easy-riding motion, not affected by the vibrations or horse motion of the shafts, and which is of simple and desirable construction. These objects are attained by the novel combination and arrangement of parts set forth in the following specification and claims, reference being had to the accompanying drawings, in which—

Figure 1 is a side view of our improved road-cart. Fig. 2 is a detached perspective view of the front end of the carrying-springs, showing the manner of their attachment to the transverse bar, to which the forward end of the body is secured. Fig. 3 is an end view of the adjustment and seat blocks, showing the attachment of the carrying-springs to the axle of the cart. Fig. 4 is a vertical cross-section of the same, taken on the plane indicated by the dotted line $x-x$ of Fig. 3. Fig. 5 is a side view of the shaft attachment to the axle of the cart. Fig. 6 is a vertical cross-section of the same, taken on the line $y-y$ of Fig. 5. Fig. 7 is a top view of the same. Fig. 8 is a detail sectional view of a part of our invention.

Referring to the drawings, 1 designates the body of the cart, the rear or seat end of which is firmly bolted to the upper arm of the carrying-springs 2 and the front end of which rests upon the transverse bar 7, which is solidly attached thereto, the said transverse bar being connected to the front end of the lower arm of the carrying-springs by means of the suspension-links 13.

The carrying-springs 2 are clipped to the axle 3, which is supported upon wheels in the ordinary manner. A small cylindrical block

or segment 9 is bolted to the lower side of the lower arm of the carrying-springs, which rests in a concave shoe 10. The bottom of said shoe is channeled out and rests upon the axle, 55 as shown in Fig. 4, the whole being clipped together and to the axle by bolts and straps in the usual manner.

The cylindrical spring-blocks 9 and the concave shoes 10 are adapted to form a ready 60 means for the proper adjustment of the body of the cart upon the axle in its relation to the height of the horse, and as the contact-surfaces thereof are plain and not toothed or corrugated, as has been the case heretofore, the 65 adjustment can be made to the exact point desired.

The shafts 4 are attached to the axle by means of the spring-plates 5, which are bolted to the top of the shafts and clipped to the top 70 of the axle, as shown in Fig. 5. The said spring-plates are re-enforced by washer-plates 8, the length of which serves to determine the stiffness or elasticity of the connection the said spring-plates are bent downward in rear 75 of the axle, the bent ends being perforated and provided with short tubes 12. The said tubes are adapted to receive and support the ends of the lower spring-plates 6, which extend and pass through the tubes 12. The said 80 extended ends are round and are provided with leather washers 11, which fit into the said tubes and are adapted to slide therein and to prevent rattling. The leather washers are pressed and held solid together between 85 collars upon the spring-plate by means of the screw-nut upon the end. It will be seen that as the leather-covered ends can neither lift nor drop in the tubes the motion of the shafts will cause the plates to spring between the 90 ends of the shafts and the tubes, and will thus supplement the action of the upper spring-plates, and that the arrangement and combination described will form a firm and yet flexible connection of the shafts to the 95 axle, well adapted to reduce the horse-motion in its effect upon the body to a minimum.

The shafts are provided with braces 15, one end of which is held by the same bolts by which the spring-plates are secured. Stay-straps 16 are also provided, one end of which is attached to the front of the body and the

other end to the shafts, and are adapted to prevent the undue movement of the body, to which it is sometimes liable.

It will be observed that the attachment of the carrying-springs to the transverse bar by means of suspension-links is adapted to give a free horizontal movement to the ends of the springs. This is found to be essential, for without this free movement the strains arising from the sudden compression and relaxation under load to which the springs are subjected cause them to break, and which is obviated thereby.

We are aware that suspension-links are the ordinary mode of attachment for carriage-springs, and are therefore not broadly new; but heretofore in the construction of road-carts the form of carrying-springs herein adopted has been given a horizontal movement by other but inadequate and defective means.

We are also aware that to adjust the body of the cart upon the axle by means of cylindrical or segmental blocks interposed between the springs and axle is not broadly new; but heretofore such blocks have been toothed or corrugated, and only capable of adjustment from one tooth to another, making it necessary also to separate the parts sufficient to permit the points of the teeth or corrugations to pass each other, while ours, being plain-faced blocks resting in plain-faced concave seats or sockets, may be adjusted with greater facility and accuracy.

Having described our invention, we claim—
1. In a road-cart, the combination of the axle 3, the shafts 4, the top spring-plates 5, the rear ends of which are bent downward and perforated, as described, and provided

with tubes 12, inserted therein, the said spring-plates being solidly bolted to the shafts and clipped to the axle, the spring-washer plates 8, adapted to stiffen and re-enforce the said spring-plates, and the lower spring-plates 6, one end of which is bolted to the shafts and the other end of which is made round and covered with leather or other suitable material, to prevent rattling, and is inserted in said tubes and adapted to slide horizontally therein, as and for the purpose specified. 40

2. In a road-cart, the combination comprising the body 1, the carrying-springs 2, the upper arms of said springs being solidly attached to said body and the lower arms pivotally connected thereto by means of the transverse bar 7 and the suspension-links 13, the cylindrical adjustment-blocks 9, solidly attached to the carrying-springs, the adjustment-block shoes 10, the said adjustment-blocks and shoes, and the carrying-springs adapted to be 50 clipped together and to the axle of the cart, the axle 3, the shafts 4, the upper spring-plates 5, solidly attached to the shafts and clipped to the axle and provided with the downward-bent ends, and tubes 12 inserted 55 therein, the lower spring-plates 6, attached to the shafts and provided with the leather-covered ends 11, which are adapted to slide horizontally in the said tubes, the washer-spring plates 8, the supporting-straps 16, and braces 70 15, as and for the purpose specified.

In testimony whereof we affix our signatures in presence of two witnesses.

WILLIAM H. WHITFIELD.
MICHAEL McCORMICK.
